his ATTORNEYS

UNITED STATES PATENT OFFICE.

ROSS R. WEST, OF SAN FRANCISCO, CALIFORNIA.

BANK VAULT.

Application filed January 26, 1925. Serial No. 4,843.

To all whom it may concern:

Be it known that I, Ross R. West, a citizen of the United States, and a resident of the city and county of San Francisco, State 5 of California, have invented a certain new and useful Bank Vault, of which the following is a specification.

The invention relates to bank vaults and particularly to the provision of a device 10 adapted to be embedded in one wall of the vault, for use as a ventilator, so that, in the event that one of the employees of the bank should be locked in the vault, either accidentally or intentionally, the opening in 15 the wall provided by the device, will permit of sufficient ventilation within the vault to prevent suffocation.

Vaults are constructed to certain rigid specifications, thereby providing a construction 20 which renders the vault substantially immune from successful attack by drills and by the flame of a metal cutting torch. It is an object of my invention to provide a ventilating device which, while providing the necessary ventilation, will not render the vault more susceptible of successful attack 25 by drilling or by the torch. Vaults are also constructed to preserve the contents against an external rise in temperature, which 30 might be caused, for instance, by the total destruction of the building in which the vault is placed, by fire. Another object of my invention is to provide a ventilating device which is heat resistant to at least the 35 same degree as the walls of the vault, so that heat will not be conducted into the vault through the ventilating device, in the event of the existence of a high temperature exterior to the vault.

Another object of the invention is to provide 40 a ventilating device which, when closed, is substantially immune from attack and which may be readily opened from within the vault.

The invention possesses other advantageous 45 features, some of which with the foregoing, will be set forth at length in the following description, where I shall outline in full that form of the invention which I have selected 50 for illustration in the drawings accompanying and forming part of the present specification. In said drawings I have shown one form of device embodying my invention, but it is to be understood that I 55 do not limit myself to such form, since the

invention, as set forth in the claims, may be embodied in a plurality of forms.

Referring to said drawings:

Figure 1 is a section through a device constructed in accordance with my invention 60 and embedded in the masonry wall of a vault.

Figure 2 is a cross section of the device taken on the line 2—2, Figure 1.

Figure 3 is an elevation of the cap employed 65 for securing the closing plug in place.

Figure 4 is an elevation of a wrench used for removing the cap and for removing the plug; a portion of the stem of the wrench 70 being broken away to reduce the size of the figure.

Vault walls are now usually made of masonry, such as concrete, and I have shown the device of my invention embedded in a 75 concrete vault wall. The device of my invention comprises a metallic sleeve adapted to be embedded in the wall of the vault and provided with means for minimizing the 80 transfer of heat through the metal of the sleeve. For this purpose the sleeve comprises two sleeve parts 4 and 5. The outer sleeve part 4 is preferably provided with an annular exterior flange 6, the outer surface of which is preferably flush with the outer 85 surface of the vault wall. The outer end of the sleeve part 4 is also preferably provided with an inner annular flange 7 having a bevelled inner edge, for reasons that will appear hereinafter. The two sleeve parts are 90 provided at their adjacent ends with outwardly extending annular flanges 12 and 13, between which there is disposed a ring 14 of suitable heat insulating material which minimizes the flow of heat longitudinally 95 through the sleeve. The two sleeve parts are secured together by bolts 15, extending through apertures in the flanges 12 and 13. The outer sleeve part 4 is provided on its inner surface, adjacent its inner end, with a screw threaded portion 16,

for reasons which will hereinafter become apparent. The outer sleeve part 4 is preferably made of a drill resistant steel, so that it will successfully withstand attack. The inner sleeve part 5 is provided on its external surface with a long screw threaded portion 17 and the part 5 is made of sufficient length, so that its inner end projects 100 beyond the inner surface of the vault wall 110

18. By making the sleeve in two parts, the inner part 5 may be made of a softer steel, so that the inner end thereof may be readily cut off to provide a complete sleeve of any desired length, depending upon the width of the vault wall. The inner sleeve parts 5 are usually made to a standard length, sufficient to fit a vault wall of the maximum thickness and, these sleeves are cut off for 10 vault walls of lesser thickness, thereby making it necessary to manufacture only one length of sleeve. The sleeve is held in place on its inner end by a nut 19 engaging the screw threaded portion 17 and bearing 15 against a washer 21 which in turn bears against the vault wall. The sleeve extends beyond the nut 19 for reasons which will subsequently become apparent.

Seated in the sleeve is a removal plug, 20 which may be removed only from within the vault. This plug is formed in two parts, comprising a head portion 22 and a body portion 23. The plug portions are hollow and are provided at their adjacent ends with 25 in-turned flanges 24—25, between which there is arranged a ring 26 of heat insulating material which minimizes the transfer of heat through the plug. The heat insulating ring 26 lies in the same plane as the 30 heat insulating ring 14, so that there cannot be a transmission of heat through the device by the heat passing alternately from the sleeve to the plug and vice versa. The inner edges of the flanges 24 and 25 are fluted for 35 as shown in Figure 2, providing seats for a wrench which may be inserted in the seats for the purpose of rotating the plug. The head portion 22 of the plug is provided on its outer surface, adjacent its inner end, 40 with a screw threaded portion which meshes with the screw threaded portion 16 on the sleeve, so that the plug is firmly and rigidly held in place and can be removed only by being rotated. The head of the plug is 45 closed at its outer end by a thick wall 27, which is preferably made of drill resistant steel. At its outer end the head is provided with a projection 28 which fits snugly into the opening in the flange 7, forming a tight 50 contact with the inclined edge 8, so that no crack is left through which material may be introduced into the vault. The hollow interior of the forward portion 22 of the plug is preferably filled with a material 29 which 55 is torch resisting or drill resisting or both, or with a metal, such as copper.

The inner end of the plug preferably extends beyond the inner end of the sleeve and, after the plug has been screwed tightly 60 in place, it is further locked in position by the cap 31, which screws onto the projecting end of the sleeve. The cap overlies the end of the plug and is preferably provided with a central projection 32 which enters the 65 plug. The cap is provided on its outer sur-

face with a slot 33, which is adapted to be engaged by the end of the wrench 34 so that the cap may be unscrewed. The plug may then be removed by inserting the wrench into the plug and into engagement with the 70 flange 25.

By this invention I have produced an aperture in the wall of the vault, which is normally securely closed and which is as immune from successful attack as the walls 75 of the vault. When ventilation within the vault is desired, the plug is removed, thereby providing a free passage through the sleeve from the interior to the exterior of the vault. The passage is of sufficient size 80 to provide sufficient air in the vault so that the person or persons trapped therein will not suffer from suffocation.

I claim:

1. The combination with a vault wall, of 85 a two-piece hollow metallic sleeve embedded in said wall and extending therethrough, heat insulation material interposed between said two pieces to minimize the flow of heat through the metal of the sleeve and a removable plug secured in said sleeve and closing the opening therethrough.

2. The combination with a vault wall, of 90 a hollow metallic sleeve embedded in the wall and extending therethrough, a two-piece removable metallic plug secured in said sleeve and closing the opening therethrough and heat insulating material interposed between said two pieces to minimize the flow of heat through the metal of the 100 plug.

3. The combination with a vault wall, of 105 a metallic sleeve embedded in and extending through the wall, an annular shoulder on the inner side of the sleeve at its outer end, a plug screwed into said sleeve and forming 110 a tight engagement with said shoulder and means accessible only from the interior of the vault for rotating said plug to remove it from the sleeve.

4. The combination with a vault wall, of 115 a metallic sleeve embedded in and extending through the wall, said sleeve being provided on its inner end with a screw threaded portion and being provided on its inner surface with a screw threaded portion, a plug engaging the latter screw threaded portion and closing the aperture through the sleeve and a cap engaging the former screw threaded portion and overlying the 120 inner end of the plug.

5. The combination with a vault wall of 125 a two-part metallic sleeve embedded in and extending through said wall, outwardly extending flanges on the adjacent ends of said two parts, a ring of heat insulating material interposed between said flanges, a two-part plug seated in and extending for the length of the sleeve and a ring of heat insulating material interposed between the 130

two parts of the plug, said two rings being disposed in the same plane.

6. The combination with a vault wall, of a metallic sleeve embedded in and extending through said wall, a plug having a hollow body and a drill resistant head screwed into said sleeve, said plug being provided with a socket adapted to receive a wrench whereby the plug may be rotated to unscrew it from said sleeve.

7. The combination with a vault wall, of a metallic sleeve embedded in and extending through said wall, a heat insulating ring

arranged in said sleeve to minimize the transfer of heat therethrough, an annular flange having a beveled inner edge disposed on the inner side of the sleeve at the outer end thereof, a plug extending through said sleeve, a projection on the outer end of the plug adapted to seat against said beveled edge, and a cap engaging the inner end of the sleeve and overlying the inner end of the plug. 15

In testimony whereof, I have hereunto set my hand.

ROSS R. WEST.
